US0D1012725S

**(12) United States Design Patent (10) Patent No.: US D1,012,725 S
(45) Date of Patent: ** Jan. 30, 2024**

(54) DOSING CONTAINER

(71) Applicant: **Berlin Packaging, LLC**, Chicago, IL (US)

(72) Inventors: **Liam Hawry**, Chicago, IL (US); **Alex Garfield**, Chicago, IL (US)

(**) Term: **15 Years**

(21) Appl. No.: **29/754,140**

(22) Filed: **Oct. 7, 2020**

(51) LOC (14) Cl. **09-01**

(52) U.S. Cl.

USPC **D9/690**; D9/688; D9/730

(58) Field of Classification Search

(57) CLAIM

The ornamental design for a dosing container, as shown and described.

DESCRIPTION

FIG. 1 is a front side perspective view showing the new design for a dosing container;

FIG. 2 is a left side perspective view thereof;

FIG. 3 is a rear side perspective view from underneath thereof;

FIG. 4 is a right side perspective view from underneath thereof;

FIG. 5 is a front view thereof, the rear view being a mirror image thereof;

FIG. 6 is a left side view thereof, the right side view being a mirror image thereof;

FIG. 7 is a top plan view thereof;

FIG. 8 is a bottom plan view thereof;

FIG. 9 is a left side perspective view showing the new design for a dosing container from FIG. 1 and illustrating a partial removal of a dosing cap;

FIG. 10 is a rear perspective view from underneath thereof;

FIG. 11 is right side perspective view from underneath thereof;

FIG. 12 is a left side view thereof, the right side view being a mirror image thereof;

FIG. 13 is a front view thereof;

FIG. 14 is a top plan view thereof;

FIG. 15 is a bottom plan view thereof;

FIG. 16 is a left side perspective view showing the new design for a dosing container from FIG. 1 and illustrating a removal of a dosing cap;

FIG. 17 is a right side perspective view from underneath thereof;

FIG. 18 is a left side view thereof;

FIG. 19 is a front view thereof;

FIG. 20 is a right side view thereof;

FIG. 21 is front view thereof;

FIG. 22 is a top plan view thereof; and,

FIG. 23 is a bottom plan view thereof.

The long short long dash lines in FIGS. 16-23 illustrate the placement of components and form no part of the claimed

(Continued)

design. The dash-dash illustrate portions of the dosing container that form no part of the claimed design.

1 Claim, 23 Drawing Sheets
